US00D452897B1

(12) **United States Design Patent** (10) Patent No.: **US D452,897 S**
Gillette et al. (45) Date of Patent: ** **Jan. 8, 2002**

(54) **PAN HEAD SHOWER HEAD**

(75) Inventors: **William J. Gillette; Timothy A. Bachman**, both of Fort Collins, CO (US)

(73) Assignee: **Water Pik, Inc.**, Fort Collins, CO (US)

(**) Term: **14 Years**

(21) Appl. No.: **29/133,989**

(22) Filed: **Dec. 12, 2000**

(51) LOC (7) Cl. **23-01**

(52) U.S. Cl. **D23/223; D23/213**

(58) Field of Search **D23/213, 223, D23/226, 229-230; 239/394, 462**

(57) **CLAIM**

The ornamental design for a pan head shower head, as shown and described.

DESCRIPTION

FIG. 1 is a right-side perspective view of a pan head shower head showing our new design;

FIG. 2 is a bottom plan view thereof;

FIG. 3 is a right side elevation view thereof, of which the left side elevation view is a mirror image;

FIG. 4 is a front elevation view thereof;

FIG. 5 is a rear elevation view thereof; and,

FIG. 6 is a top plan view thereof.
